UNITED STATES PATENT OFFICE.

WILLIAM J. CONWAY, OF CHICAGO, ILLINOIS.

SOFT-TREAD HORSESHOE.

SPECIFICATION forming part of Letters Patent No. 660,788, dated October 30, 1900.

Application filed October 21, 1899. Serial No. 734,325. (No model.)

To all whom it may concern:

Be it known that I, WILLIAM J. CONWAY, a citizen of the United States, residing at 227 East Washington street, Chicago, in the county of Cook and State of Illinois, have invented a new and useful Improvement in Horseshoes, of which the following is a specification.

My invention relates particularly to an improvement in horseshoes of the type employing an elastic tread; and my object is to provide a substantial shoe of this character the tread of which shall be readily detachable and replaceable.

15 In the accompanying drawings, Figure 1 represents a bottom plan view of the shoe without the tread; Fig. 2, a section at line 2 of Fig. 1 with the tread supplied, and Fig. 3 a similar section at line 3 of Fig. 1.

20 The shoe comprises, essentially, an upper curved plate *a*, constituting a hoof-plate, outer and inner peripheral flanges *a'* *a''* on the lower surface of said plate and forming a central tread-section-receiving channel *a³*, tread-section-retaining lugs *a⁴*, provided with beveled surfaces *a⁵* and retaining-shoulders *a⁶* and projecting from the lower edges of the flanges *a'* *a''*, and a central tread-section *a⁷* of elastic material, which affords a projecting 30 antislippage tread-surface.

The shoe is provided with nail-holes *b*, which in the form of shoe shown are inside the flange *a'*. In this construction the shoe is nailed to the hoof before the tread-section 35 is put in place. The flanges *a'* *a''* preferably converge slightly, each being at an angle to the plate *a*, except at the front of the shoe, where the inner surface of the flange *a'* becomes substantially perpendicular to the 40 plate, as shown in Fig. 2. At this point an upturned toe-lug *b'* is shown, this being a

common provision. The tread-section retainers *a⁴* may be changed in form, as by increasing their length, the essential feature being that there be opposed retainers projecting 45 from the flanges *a'* *a''* of such shape as to permit the tread-section to be pressed between them in putting it in place, but to prevent it from being withdrawn after being pressed into place. After a tread-section has become 50 so far worn as to render its replacement desirable it may be torn from its socket and a new section readily pressed into place without removal of the shoe from the horse's foot.

The metallic portion of the shoe may be 55 cast and malleableized or the shoe may be drop-forged, in which latter case the lugs *a⁴* would be turned to their horizontal position after the forging operation. The tread-section may be of any suitable material which 60 will yield at its lateral surfaces to pass the lugs *a⁴* and then expand inside or above said lugs to prevent accidental detachment.

What I claim as new, and desire to secure by Letters Patent, is—

A horseshoe comprising a hoof-plate provided upon its under side along the inner and outer edges throughout with inwardly-inclined walls forming a recess, a yielding or elastic tread-section for the recess, the walls 70 of the recess having projecting from their inner surfaces toward the lower edges, integral inflexible lugs having inwardly-inclined surfaces and inner retaining-shoulders, the inclined surfaces of the lugs permitting ready 75 insertion of the tread-section while the shoulders retain it in place.

WILLIAM J. CONWAY.

In presence of—

D. W. LEE,
M. S. MACKENZIE.
